CLAIM

The ornamental design for a mouthguard, as shown and described.

DESCRIPTION

FIG. 1 is a front view of a mouthguard showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is another left side view thereof, showing the mouthguard in an alternative configuration;

FIG. 8 is another right side view thereof, showing the mouthguard in an alternative configuration;

FIG. 9 is an exploded top perspective view thereof, showing the upper and lower parts of the mouthguard being separated; and,

FIG. 10 is an exploded bottom perspective view thereof, showing the upper and lower parts of the mouthguard being separated.

The dash-dash broken lines in the drawings depict portions of the mouthguard that form no part of the claimed design. The dot-dash broken lines in the drawings denote the boundaries of the claimed design and form no part of the claimed design.

1 Claim, 10 Drawing Sheets
